UNITED STATES PATENT OFFICE.

RALPH A. LIGHT AND JOSEPH W. PRICE, JR., OF PHILADELPHIA, PENNSYLVANIA, AS
SIGNORS TO THE UNITED STATES METALLIC PACKING COMPANY, OF PHILADEL-
PHIA, PENNSYLVANIA, A CORPORATION OF PENNSYLVANIA.

TRACK SANDER.

Application filed October 27, 1922. Serial No. 597,240.

To all whom it may concern:

Be it known that we, RALPH A. LIGHT and JOSEPH W. PRICE, Jr., citizens of the United States of America, and residents of 5 Philadelphia, in the county of Philadelphia, in the State of Pennsylvania, have invented certain new and useful Improvements in Track Sanders, of which the following is a true and exact description, reference being 10 had to the accompanying drawings, which form a part thereof.

Our invention relates to track sanders used in connection with locomotives and has for its object to provide a sander of simple 15 and efficient construction and in which the air blast nozzle or nozzles provided for lifting the sand out of the trap and delivering it to the delivery passage are at the same time located in such a way as to act with 20 great efficiency on the sand and to be completely protected against the entry of sand into the nozzle or nozzles.

The nature of our improvement will be best understood as described in connection 25 with the drawing which is a sectional elevation of our improved track sander and in which—

A indicates the casing making up the body 30 of the sander and having an opening B at its top through which it is connected with an elevated sand box. Below this opening the casing has formed in it a sand receiving bowl E and a bowl opening G separated from the bowl by an upwardly extending 35 wall portion C and connected with the bowl portion by a passage F extending over the top of the wall C. e indicates the normal angle of rest of the sand in the bowl portion of the casing. H is an opening in the bottom 40 of the bowl portion normally closed by screw plug I. J is a threaded opening formed through the top of the passage F and connected, as shown, with two nozzle passages J' and J'', the nozzle passage J' being directed toward the bowl portion of the casing and the nozzle passage J'' being directed toward the outlet passage G. K is the air pipe leading to the opening J and in which, by preference, we place a valve 45 casing L having a port L' in connection with which operates an adjustable needle valve M. This valve is entirely distinct from the ordinary controlled valve by which 50 air is admitted and cut off from the pipe K

and has for its function to regulate the pressure of air delivery through the pipe K to the nozzles J' and J''.

In operation the sand trap has its bowl portion E normally filled with sand up to the level indicated at e. When it is desired to deliver sand to the track, air is turned on through the pipe K and a jet of air is delivered through the nozzle J' directly against the sand in the bowl with the result of picking up the sand and, through an eddying action, carrying it through the passage F and delivering it to the outlet passage G. This action is improved and accelerated by providing the second air nozzle J'' directed into the outlet passage G.

It is a marked feature of our improved construction that the air nozzles are located in the passage F and entirely outside of the bowl portion in which the sand is normally retained. There is, consequently, no liability of the sand getting into the nozzles' way. Its presence would result in more or less choking of the nozzle and some times in the stoppage of the nozzle.

Having now described our invention, what we claim as new and desire to secure by Letters Patent, is:

1. A track sander comprising a trap adapted to receive sand by gravity from a sand box and having a bowl wherein the sand is normally retained, a discharge opening separated from the bowl by an upwardly extending wall and a passage connecting the bowl and discharge opening over the wall, in combination with a blast nozzle located in the connecting passage above the normal sand level therein and directed toward the bowl portion of the trap.

2. A track sander comprising a trap adapted to receive sand by gravity from a sand box and having a bowl wherein the sand is normally retained, a discharge opening separated from the bowl by an upwardly extending wall and a passage connecting the bowl and discharge opening over the wall, in combination with a blast nozzle located in the connecting passage above the normal sand level therein and directed toward the bowl portion of the trap and a second blast nozzle also located in the passage and directed toward the discharge opening.

3. A track sander comprising a trap

2
adapted to receive sand by gravity from a sand box and having a bowl wherein the sand is normally retained, a discharge opening separated from the bowl by an upwardly extending wall and a passage connecting the bowl and discharge opening over the wall, in combination with a blast

nozzle located in the connecting passage above the normal sand level therein and directed toward the bowl portion of the trap ¹⁰ and an adjustable needle valve controlling the flow of air to the nozzle.
